5,844

UNITED STATES PATENT OFFICE.

FRIEDRICK WESEMAN, OF BROOKLYN, ASSIGNOR TO TAYLOR & CO., OF NEW YORK, N. Y.

DESIGN FOR BURIAL-CASKET.

Specification forming part of Design No. 5,844, dated May 7, 1872.

Specification describing a Design for Burial-Caskets, invented by FRIEDRICK WESEMAN, of Brooklyn, in the State of New York.

The nature of my design is fully represented in the accompanying drawing, to which reference is made.

A represents the body of the casket, and B its cover or lid. I make the ends of the body, for the main part of its height, convex, as shown at *c*, and the upright corners concave, as shown at *d*. The remaining part of the body between the line *xx* and the lid projects over the main part at all sides, and has its ends, sides, and corners concaved, as shown at *ef*. The projecting edge of the bottom I make with a concave molding, and I also prefer to make a concave molding on the projecting edge of the upper part of the body, as seen at *g*. The lid B has also a concave molding at its edge, as seen at *h*.

The upper or concave part may be secured to the lower part of the body in any way desired. I prefer to connect them by screws.

The lid proper, marked B, I hinge to such upper part, and it may have a lock to fasten it thereto; but I do not confine myself to any such details of construction, my present invention relating only to the configuration.

What I claim as my invention is—

A design for a burial-casket, having the outwardly-curved ends to the body and cover, the concaved corners, and the concave moldings, substantially as shown and described.

FRIEDRICK WESEMAN.
